WAAREN- UND MASCHINENFABRIK, OF DUSSELDORF-DERENDORF, GERMANY.

HYDRAULIC BRAKE FOR GUNS HAVING A RECOILING BARREL.

1,082,717.

Specification of Letters Patent. Patented Dec. 30, 1913.

Application filed January 16, 1907. Serial No. 352,601.

To all whom it may concern:

Be it known that I, KARL VÖLLER, engineer, a subject of the German Emperor, residing at 17 Jülicherstrasse, Dusseldorf, Germany, have invented certain new and useful Improvements in Hydraulic Brakes for Guns Having a Recoiling Barrel; and I do hereby declare the following to be a full, clear, and exact description of the invention, such as will enable others skilled in the art to which it appertains to make and use the same.

This invention relates to a hydraulic brake for guns having a recoil barrel of the kind described in my Patent No. 755418, in which the cross section of the passage for the flow of the braking fluid is automatically increased or diminished accordingly as the elevation of the barrel is varied.

According to the present invention an annular slide in the present example forming part of the piston capable of rotation and at the same time of sliding coaxially with the piston rod, is so arranged that at the beginning of the recoil it brings into register the passages for the flow of the braking fluid with corresponding passages in the piston rod, while in its other position when the return begins, it brings into register other passages with further passages in the piston rod for the flow of braking fluid. The adjustment of the initial cross section of the passages corresponding to the required length of recoil is automatically controlled, as in the aforesaid specification, by the rotation of the piston rod according to the given elevation, and the gradual closing during the recoil and the gradual opening during the return, is effected by guiding the annular slide in a curved groove in the braking cylinder.

In the accompanying drawings, are shown several embodiments of the invention by way of illustration.

In these drawings Figures 1 and 1^a and Figs. 3 and 3^a are developed longitudinal sections taken on the line 1 and 3, Figs. 2 and 4 respectively; Figs. 5, 7 and 9 are longitudinal sections; Figs. 2, 4, 6, 8 and 10 are transverse sections through Figs. 1, 3, 5, 7 and 9 respectively; Fig. 11 shows diagrammatically the different stages of the registering of the passages for the form of construction illustrated in Figs. 1, 1^a and 2; and

Fig. 12 is a similar view applicable to the other embodiments.

In the construction shown in Figs. 1, 1^a and 2, the brake cylinder *f* which is constructed and connected with the gun barrel in the known manner, contains the piston rod *b*; the latter is fixed as usual in the front end plate of the gun carriage and is automatically turned when the elevation of the barrel is varied in the manner set forth in the aforesaid patent. On the head *b'* of the piston rod *b* there is free to turn an annular slide *a* which is guided in curved grooves in the brake cylinder in such a manner that it is rotated during the recoil and during the return. This slide is so faced on its periphery that it acts as the brake piston. It has two sets of passages *c* and *h* which can come into register with the passages *d* and *g* through the head of the piston rod, that is to say either the set of openings *c d* come into register, or the set of openings *g h*. These two sets of openings may differ in cross sectional area, one set serving to assist in throttling the braking fluid during recoil and the other during counter-recoil. In the brake cylinder *f* there is a regulating rod *k* fixed at its rear end. It is guided in the hollow piston rod, and is provided with a bore *s*, in order that during the recoil and return it may not effect any braking action of the piston rod *b*. The rod *k* has its surface turned down at its middle part to the form of a bi-concave curve, so that the braking fluid can pass through the passages *c d* or *g h* from one side of the piston to the other. The form given to the surface of the rod corresponds with the conditions that prevail during the movement of the gun barrel, so that it is possible, by selecting a suitable curvature for the surface, to control the speed of passage of the braking fluid at every instant of the recoil or the return to correspond with the prevailing pressure and resistance.

Fig. 1 indicates the position of the annular slide at the end of the return, Fig. 1^a indicating the position at the beginning of the recoil. During the recoil, the brake cylinder *f* together with the regulating rod *k* fixed to it, slides backward, while the piston rod *b* remains stationary. The annular slide *a* is thus pressed against the rear flange of the head *b'* of the piston rod; so that its

passages *h* come into register with the passages *g* of the piston rod. The braking fluid can now flow from the front part *i* of the braking cylinder, through passages *g* and *h* 5 to the rear part *e* of the cylinder. It passes on its way through the space between the curved surface of the rod *k* and the bore of the head of the piston rod, the dimensions of which space at every moment depend on the 10 curve given to the regulating rod to suit the pressure and resistance.

The degree to which the passages *g* and *h* register at the beginning, depends upon the amount of rotation that the piston rod *b* 15 has received correspondingly with the elevation. These passages do not remain in the same relative position during the whole recoil, but move in relation to each other during the progress of the recoil owing to 20 the rotation of the annular slide *a*, until the cross section of the passage is so small that the barrel and brake cylinder remain stationary. This relative shift is diagrammatically shown in Fig. 11, where I is the 25 position at the beginning of the recoil, it being supposed that the barrel is in the horizontal position. The cross hatching shows that the passages are in complete registration.

30 III indicates that the passages are completely out of registration, while II shows an intermediate position which is either attained during the change from I to III, or is the result of the elevation of the barrel to 35 a certain angle.

In the return, as Fig. 1 shows, the annular slide *a* is pressed against the front flange of the head of the piston rod, so that the passages *g* and *h* are separated from each 40 other, and instead the passages *c* and *d* come into registration. Here also the throttling of the braking fluid by the curved form of the regulating rod *k* occurs. At the same time the flow is also regulated by the rotation of the annular slide during the return.

Figs. 3-10 show modifications of the invention in which a regulating rod like that shown in Figs. 1 and 2 is not used. Instead, the regulation corresponding with the conditions of pressure and resistance is attained by curving the boundaries of the passages for the fluid. In Fig. 12 this method is 50 illustrated for three different positions.

In Figs. 3, 3^a, and 4 the annular disk *a'* 55 slides axially on the head *b*³ of the piston rod, and is turned on the latter by the curved grooves in the brake cylinder during the recoil and the return. Fig. 3 shows the position of the piston during the return, 60 while Fig. 3^a shows the position during recoil. The passages in the head of the piston rod form a direct connection between the passages of the slide *a'* and the front and rear part of the brake cylinder. The 65 passages *g'*, in this form of the device, lead to

a central concavity or recess *j* in the end of the piston head, while the passages *c'* open directly into the space *e* of the cylinder, and the passages *d'* lead to the space *i* of the cylinder instead of merely extending transversely through the piston head. 70

In the form shown in Figs. 5 and 6, a cylinder *m* is secured to the end of the piston rod, and this cylinder is provided with lateral ports *o* near its forward end and similar ports *p* near its rear end. The cylinder is secured to the piston rod by having a forward extension *k'* threaded into the rear end of the piston rod, as clearly shown, and adjacent to the ports *o* it is provided with an internal bridge or valve seat, *l*. The slide *a* is mounted to rotate on the cylinder *m* and is guided in spiral grooves in the cylinder. A ring *a*³ is fitted in the end of the slide and acts as a stop to limit the movement of a valve having a stem *n'* playing in the extension *k'* of the cylinder, a disk portion *n* adapted to engage the bridge or valve seat *l*, and a spider or ring portion *n*² slidably fitting within the cylinder and adapted to cover the ports *p* therein. The slide is also provided with lateral ports adapted to register with the ports *o*, *p*, in the cylinder *m*, as shown and as will be readily understood. 80

The functions which the slide in the previous constructions fulfilled by its axial movement, are here transferred to the valve *n*. The longitudinal section shows the piston and valve in the position which they have during the return, the passages *p* being opened for this purpose. During the recoil these passages are closed by the cylindrical part of the valve as indicated by the dotted lines, and the passages *o* for the recoil come into action. In both cases the valve *n* is opened or closed by the pressure of the braking fluid as the barrel returns or recoils. 90

In Figs. 7 and 8 a slide *r* arranged within the cylinder *m* is substituted for the valve. In this case the slide *r* is subject to the action of a spring *q* arranged between the head of the slide and the end of the cylinder *m*, so that during recoil the rear ports in the cylinder will register with the ports *p'* in the slide *r* and the front ports *o* in the cylinder will be closed by the slide, as shown. During the return the braking fluid presses against the slide and compresses the spring *q*, thereby forcing the said slide *r* forward and bringing the ports *o'* therein into registry with the ports *o* in the cylinder *m*, as will be readily understood. In this case the slide *a* has the same construction as that shown 100 in Figs. 5 and 6. 110

The form shown in Figs. 9 and 10 is similar to that just described, with this difference, that the slide *r* is arranged outside of instead of within the cylinder *m*. The an- 120 130

nular slide *a* which, as in the preceding constructions is guided in grooves in the brake cylinder, extends into the interior of the cylinder *m* and is bayonet-jointed therewith. 5 This connection can be released only after the bolt that connects the piston rod with the end plate has been removed.

Figs. 9 and 10 show the arrangement of the parts in the recoil position, the spring 10 *q* is compressed owing to the pressure of the fluid on the front end of the slide *r*, the ports *p* are opened, for the recoil so that the braking fluid can flow from the front part of the braking cylinder to the rear part. During 15 the return the spring *q* presses the slide *r* forward, so that the return ports *o* are opened while the ports *p* are closed. A flange *u* on the piston rod limits the position of the slide *r* during the return.

Having now particularly described and ascertained the nature of our said invention and in what manner the same is to be performed, we declare that what we claim is:—

1. In a hydraulic brake for guns, the combination, with a cylinder, a piston mechanism within said cylinder and having dissimilar sets of ports comprising radial passages, one for the flow of braking fluid from one side of the piston to the other during the recoil movement and the other for the contrary flow of the same fluid during the counter recoil movement, of means controlled by the pressure of the braking fluid in both directions, and arranged to open

one set of ports and close the other during 35 movement in one direction and vice versa during movement in the other direction.

2. In a hydraulic brake for guns, the combination of a piston part having two dissimilar ports comprising radial passages, 40 and a slide carried by the said piston part and arranged to be shifted under the pressure of the braking fluid to cause either of said ports to be closed when the other port is open. 45

3. In a hydraulic brake for guns, the combination with a brake cylinder, of a piston part within the same provided with two sets of ports for the passage of braking fluid, a slide mounted on the piston to have an axial 50 and a rotary movement thereon, the said slide being provided with two sets of ports for the passage of the braking fluid and being open to the pressure of the braking fluid, whereby it will move axially upon the piston part to cause its own ports to register alternately with the corresponding ports in the piston part, and means on the braking cylinder to rotate the slide and thereby cut off the flow through the registering ports. 55

In testimony whereof I have hereunto affixed my signature in the presence of two witnesses.

KARL VÖLLER.
